UNITED STATES PATENT OFFICE.

JAMES J. DEVENNY AND CHARLES F. DEVENNY, OF PHILADELPHIA, PENNSYLVANIA.

SASH-JOINT.

1,242,427.

Specification of Letters Patent. Patented Oct. 9, 1917.

Application filed August 9, 1917. Serial No. 185,286.

To all whom it may concern:

Be it known that we, JAMES J. DEVENNY and CHARLES F. DEVENNY, citizens of the United States, residing at Philadelphia, 5 county of Philadelphia, and State of Pennsylvania, have invented certain new and useful Improvements in Sash-Joints, of which the following is a specification.

Our invention consists of an improved 10 sash joint. One object of our invention is to provide a sash joint which can be used with advantage as a part of the construction of window sashes, doors, transoms, etc.

Another object of our invention is to provide 15 a sash joint which will be strong and durable and which can be quickly and easily manufactured.

These objects, and other advantageous ends which will be described hereinafter, 20 we attain in the following manner, reference being had to the accompanying drawings in which—

Figure 1 is a face view of one of the muntins which forms a part of our improved 25 sash joint.

Fig. 2 is a view of similar nature to Fig. 1 showing said muntin bent into an interlocking position.

Fig. 3 is a transverse section on the line 30 3—3 of Fig. 2.

Fig. 4 is a face view of the other of the muntins which forms a part of our invention and which is designed to interlock with the muntin as shown in Fig. 2.

Fig. 5 is a view showing the muntin illustrated in Fig. 4 in a position ready to be interlocked with the muntin illustrated in Figs. 1 to 3 inclusive.

Fig. 6 is a view of similar nature to Fig. 40 5 showing the muntins in their finished interlocked positions.

Fig. 7 is an inverted plan view of Fig. 6.

Referring to the drawings, 1 and 2 represent the muntins forming a part of our improved sash joint and which are preferably made out of metal. The muntin 1 has an elongated head 3 from which projects a flat rib 4. This rib 4 has a slot 5 which extends from the bottom surface 6 of the head 3 toward the edge surface 7 of the rib 4. This slot 5 is preferably rectangular as clearly shown in Fig. 1.

The rib 4 is split at 8, said split extending from the bottom of said slot to the edge surface 7 and in alinement with the surface 9 of the slot 5, thus a lug 10 is provided and

is formed by the metal between the bottom of the slot 5 and the edge surface 7.

The head 3 is cut away as shown at 11 with the exception of a portion 12 which is substantially of the same thickness as the rib 4 and of a width substantially equal to the width of the slot 5. The muntin 2 has a head 13, preferably of the same shape as the head 3. This head 13 has a flat rib 14 65 extending therefrom and is cut away at 15 in a manner similar to the cut 11 of the head 3.

The head 13 is notched at 16 throughout its entire depth and the rib 14 is notched at 17, said notch extending inwardly from the edge surface 18 and in alinement with the notch 16 as clearly shown in Fig. 4.

The width of metal between the inner ends of the notches 16 and 17 is substantially identical to the length of the slot 5, and the width of the slot 5 is substantially the same as the thickness of the rib 14 of the muntin 2. Thus, when the muntins 1 and 2 are positioned at right angles, one to the other, the muntin 1 can be slipped downwardly over the muntin 2, the bending of the muntin 1 being sufficient to allow the portion 18^a of the muntin 2 to pass through the opening 19 into the position shown in Fig. 5, and so that the lug 10 extends into the notch 17. The muntin 1 is then bent into its normal position, such for example as shown in Fig. 1, and thereby the two muntins are interlocked, this position being 85 shown in Figs. 6 and 7.

While we have described our invention as taking a particular form, it will be understood that the various parts of our invention may be changed without departing 95 from the spirit thereof, and hence we do not limit ourselves to the precise construction set forth, but consider that we are at liberty to make such changes and alterations as fairly come within the scope of the appended claims.

Having thus described our invention, what we claim as new and desire to secure by Letters Patent is:

1. A sash joint including two muntins, one muntin having a slot extending transversely within its width and being split, said split extending from said slot to one edge to form a lug between one end of said slot and said edge, the other of said muntins having a portion designed to fit within said slot and being provided with a notch into

which said lug extends, substantially as described.

2. A sash joint including two muntins, one muntin having a slot extending transversely within its width and being split, said split extending from said slot to one edge to form a lug between one end of said slot and said edge, the other of said muntins having a portion designed to fit within said slot and being provided with a notch into which said lug extends, said latter mentioned muntin having a second notch, said first-mentioned muntin having its portion which is oppositely disposed from said lug adapted to enter said second-mentioned notch, substantially as described.

3. A sash joint including two muntins each having an elongated head, and a rib projecting from said head, one of said muntins having a slot formed in its rib, said slot stopping short of the outer edge surface of said rib, said rib being split from said edge surface into said slot to provide a lug, the other of said muntins having notches cut respectively through said head and inwardly from the outer edge surface of its rib, said latter mentioned muntin having the portion between said two notches designed to extend within said slot, said lug being adapted to enter the notch which extends inwardly from said edge surface, the head of said first-mentioned muntin being cut away for a portion of its thickness to provide a portion adapted to enter the other of said notches on the second-mentioned muntin, said split being formed in alinement with one side surface of said slot, substantially as described.

vide a portion adapted to enter the other of said notches on the second-mentioned muntin, substantially as described.

4. A sash joint including two muntins each having an elongated head, and a rib projecting from said head, one of said muntins having a slot formed in its rib, said slot stopping short of the outer edge surface of said rib, said rib being split from said edge surface into said slot to provide a lug, the other of said muntins having notches cut respectively through said head and inwardly from the outer edge surface of its rib, said latter mentioned muntin having the portion between said two notches designed to extend within said slot, said lug being adapted to enter the notch which extends inwardly from said edge surface, the head of said first-mentioned muntin being cut away for a portion of its thickness to provide a portion adapted to enter the other of said notches on the second-mentioned muntin, said split being formed in alinement with one side surface of said slot, substantially as described.

In testimony whereof we have signed our names to this specification in the presence of two subscribing witnesses.

JAMES J. DEVENNY.

CHARLES F. DEVENNY.
